UNITED STATES PATENT OFFICE.

HENRY J. GAISMAN, OF NEW YORK, N. Y.

DESIGN FOR A SAFETY-RAZOR BLADE.

59,345.

Specification for Design.

Patented Oct. 11, 1921.

Application filed April 30, 1921. Serial No. 465,840. Term of patent 14 years.

To all whom it may concern:

Be it known that I, HENRY J. GAISMAN, a citizen of the United States, and resident of New York, borough of Manhattan, county of New York, State of New York, have invented a new, original, and ornamental Design for a Safety-Razor Blade, of which the following is a specification, reference being had to the accompanying drawing, forming part thereof.

Figure 1 is a perspective view of a safety razor blade showing my new design, and Fig. 2 is a section on the line 2, 2 in Fig. 1.

I claim:

The ornamental design for a safety razor blade, substantially as shown.

Signed at New York, in the county of New York and State of New York, this 28th day of April, 1921.

HENRY J. GAISMAN.
